UNITED STATES PATENT OFFICE

2,577,747

METHOD OF MAKING TURBINE BLADES

Emil F. Gibian, East Cleveland, Ohio, assignor to
Thompson Products, Inc., Cleveland, Ohio, a
corporation of Ohio

Application September 25, 1946, Serial No. 699,114

4 Claims. (Cl. 29—156.8)

1

My invention relates to the production of blade members or buckets for wheels of turbine engines, such as turbo-Jet engines and jet-propulsion engines.

The terms "turbine blade" or "turbine bucket" as used herein are intended to cover blades or buckets for driven as well as for driving members of engines and therefore, for example, generically cover blades or buckets for compressor wheels and turbine wheels of jet propulsion engines.

Heretofore, blades for gas turbine engines and the like have been made by a process of forging blade blanks and machining the blanks to the prescribed dimensions. In the forging operations it is expensive and difficult to achieve a final or forged blank wherein the edges are accurately dimensioned relative to each other and the remainder of the blade. This has caused considerable difficulty in properly establishing the points of reference with respect to which subsequent machining operations such as milling, broaching, polishing, etc. are to be made. As a consequence of this fact, it is necessary to allow an excessive amount of material to be removed in these operations in order that errors resulting from inability to accurately locate the true center line of the blade shall not result in an inadequate thickness of material at any one side. This not only increases the total amount of material used but also requires that additional material be removed in the machining operations.

It is an object of my invention to provide an improved method whereby blades for turbines and the like may be manufactured.

It is a further object of my invention to provide improved means for and methods of accurately locating the axes of a cast or forged turbine blade blank so that subsequent machining operations may be most expeditiously performed.

Further it is an object of my invention to provide an improved method of making turbine blades and the like wherein minimum excess material is required between the initial casting or forging operation and the final blade structure.

Another object of my invention is to provide an improved method of making turbine blade structures and the like which locates the axes of the blade in a simple and accurate manner without requiring forgings, castings, etc. having unreasonable dimensional tolerances.

Another and further object of my invention is to provide an improved method of making turbine blades and the like which is suitable for use with jigs and other fixtures in manufacturing processes, thereby improving the quality and quantity of the output therefrom and achieving a corresponding reduction in cost of the final product.

Still another object of my invention is to provide an improved turbine blade blank from which turbine blades and the like may be manufactured in a convenient and reliable manner and which

2

may be sold and marketed as a separate article of commerce for use in machining turbine blades to various dimensions as the purchaser desires.

The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawings.

On the drawings:

Figures 1 and 2 are side and plan views, respectively, of a headed rod or rough blade blank prior to forging operations.

Figures 3 and 4 are plan views of the die and punch members, respectively, used in the forging operation.

Figure 5 is a longitudinal cross section of the blade, punch and die members during the forging operation.

Figure 6 is a bottom plan view of the forged blade blank.

Figure 7 is a top plan view of the same blank with the ends trimmed.

Figure 8 is a top plan view of a jig for use in machining the ends of the root portion of the blade.

Figure 9 is a longitudinal cross section view of the jig taken along the line IX—IX of Figure 8 and with the rough blade forging mounted thereon and positioned for machining operations.

Figure 10 is an end elevational view of a production gauge suitable for use in checking the blade forging after the ends of the root portions have been trimmed.

Figure 11 is a vertical cross-sectional view of a drill jig for placing a reference hole in the blade forging.

Figures 11a and 11b are enlarged partial horizontal cross-sectional views showing how the forging is mounted in the drill jig of Figure 11.

Figure 12 is a view of the blade mounted for grinding the airfoil section.

Figure 13 is a bottom plan view of the blade after further milling operations.

Figure 14 is a view similar to Figure 13 but showing the blade after a final broaching operation.

Figure 15 is a view of the blade after the end has been removed; and

Figures 16 and 17 are views of the final blade. As shown on the drawings:

Figures 1 and 2 show, respectively, elevation and plan views of a forged blank from which a bucket, blade, or the like is to be fashioned. This blank consists of two integral portions, the root-forming portion 20 and the blade-forming portion 21. As shown in the figure, the blade-forming portion of the blank is in the form of an

elongated cylindrical rod whereas the root-forming portion is in the form of an elongated head on one end of the rod with a major axis perpendicular to the axis of the blade portion and extending on each side thereof at one end of the blade portion, the root-forming portion being thicker in the side views than the blade-forming portion to allow for the additional thickness necessary at the root portion of the final blade.

The die and punch members from which the blank of Figures 1 and 2 is converted to a final forged blank, are shown in Figures 3 and 4 respectively. In the case of the die member of Figure 3, it will be observed that a flat recess portion 22 is provided to act upon and receive the blade portion 21 of the rough blank. This portion contains a suitable dimple recess 23 for forming a localized reference button in the blade portion of the final forged blank, this button being located along the axis of the final blade. In addition, a recess 24 for a boss is provided. The purpose of the button formed from recess 23 and the boss formed from recess 24 will be described in further detail hereafter.

In addition to the blade receiving portion of die 22, a root portion shown generally at 25 is provided. This portion consists of an elongated narrow recess extending at a slight angle relative to the axis of the blade portion of the die 22. The purpose of this angle is to give the top of the final blade the slight taper ordinarily desirable in blade mountings for gas turbines and the like. At the center of the root portion 25 a dimple recess 26 is provided for a root button, this recess being located on the axis of the blade portion 22 of the die and at a point thereon having a predetermined relation to the root portion. Viewed differently, this recess is located on the blade axis at a fixed distance relative to the airfoil sections of the finished blade.

The punch of Figure 4 is shaped to coact with the die of Figure 3 so as to shape the opposite surface of the final forging. This member has a flat blade forming protuberance 27 acting upon the portion 21 of the blank to flatten it into the recess 22 of the die while imparting an airfoil sectional shape thereto with a slight helical twist or pitch. The punch portion 27 is free from dimple recesses but does have a boss forming recess 28 aligned with die recess 24. Recess 28 unlike the recess in the die member is provided with lateral extensions. These extensions provide dam-like recesses which stop free flow of metal out of the ends of the die members.

The root portion of the punch, designated generally at 29, is identical with the root portion 25 of the die except that the recess 26 for the root button is omitted.

The die and punch members when placed in opposed relation for forging operations form mating blade shaping cavities and protuberances for the production of the forged blade as shown in the cross-sectional view of the blade and members in Figure 5. It will be evident from this figure that the root portion of the blade, designated as 30, has symmetrical top punch formed and bottom die formed halves except that button 31 is produced on the bottom die formed half. Similarly, button 32 of the blade portion 41 extends only on the same side as button 31. Recesses 24 and 28 in the die and punch members provide a symmetrical boss 33 on the forging.

Figure 6 shows a view of the finished forging taken from bottom and showing the location of buttons 31 and 32.

Figure 7 shows a similar view of the top of the blade except that the extending portion 34 has been removed.

An important feature of this invention resides in providing buttons 31 and 32 on the root and blade portions of the final forging respectively. It will be observed that these buttons located the axis through the center of the blade forging. However, these buttons need not be located in the forging member with an excessively high degree of accuracy inasmuch as a certain amount of excess material may economically be allowed for the forging processes and it is only necessary to locate the buttons so as at all times to prevent machining the blade in a manner to exceed these allowances. Thus, while these buttons act as guides they need not be guides of extreme accuracy and can readily be made by the forging process. In one method of applying this invention, for example, these buttons are approximately one-eighth inch in diameter and extend upwardly from the root and blade surfaces approximately the same distance. It should be observed that punch and die wear tends to be uniform on all sides of the buttons. Thus, when these buttons are inserted into V-notches provided for the purpose, the blade forging is accurately positioned despite the fact that there may be slight imperfections in the exact surface of the buttons themselves. This feature will be evident from the following discussion illustrating the process used in manufacturing a typical turbine blade from the final forging.

The first operation in the machining process is to trim the ends of root portion 30 relative to the axis through buttons 31 and 32. A plan view of a jig useful for this purpose is shown in Figure 8. This jig has mounting holes 35 provided for attachment to a suitable table and two upwardly extending portions, shown generally at 36 and 37, respectively. Portion 36 includes member 38 which has a flat upper surface and a recess 39 located therein. This recess is of V-notch construction to cooperate with the button 31 located on the root portion of the finished forging. Portion 37 has slot 40 located in the upper surface thereof and extending along an axis passing through recess 39. This slot is of V-shape to cooperate with button 32 on the blade portion of the finished forging.

A cross-sectional view of the jig of Figure 8 with the forging located thereon is shown in Figure 9. From this figure it is evident that the forging is positioned along the axis between the buttons 31 and 32 by button 31 which is located on the root portion of the blade whereas button 32 on the blade portion prevents rotation about this point and establishes the central axis through the blade. Thus, the ends of the root portion 30 of the finished forging may be ground with respect to the fixture inasmuch as buttons 31 and 32 accurately position the forging with respect thereto. The resultant blade may be checked with a gauge such as shown in Figure 10. In this gauge a slot 41 is provided in which buttons 31 and 32 may slide, this slot being of a V-notch construction. Gauge members 42 are located on each side of slot 41 and are separated therefrom by the amount of the desired blade length. Thus, by sliding the ground blade blank through this gauge the degree of accuracy of machining thereof may readily be evaluated, the blade refusing to pass if the length of the root portion is excessive on either side of the axis through buttons 31 and 32 and an air space show-

ing if the root portion has been ground too short on either side. Thus, the root is accurately machined not only to a predetermined total length but to a predetermined length on each side of the final blade axis as represented by the position of buttons 31 and 32.

A drill jig suitable for use in connection with a further step in the manufacture of the final turbine blade is shown in cross-section in Figure 11. It is the purpose of this jig accurately to place a hole in the end of boss 33 of the blade forging. To this end, a recess 43 is provided, this recess being shaped so as to cause button 31 on the root portion of the blade to cooperate with a fixed V-shaped notch, thereby positioning the root portion of the blade on the fixture. A cross-section view of this engagement is shown in Figure 11a. Similarly, member 44 against which button 32 is pressed has a vertically extending V-shaped notch which appears in cross-section as shown in Figure 11a. This positions the button 32 with respect to the drill jig so as to prevent rotation of the blade about button 31. Inasmuch as both buttons 31 and 32 are positioned relative to the axis of drill 45 by reason of the above-described notches, the hole placed in the boss 33 is also accurately positioned with respect thereto so that this hole may subsequently be used in the machining processes. A swingably mounted member 46 is provided to hold the blade forging 47 against member 44 and is provided with resilient means such as spring 48 (shown in dashed lines) to swing it away from the forging when released. Member 49 and bolt 50 may be used to lock member 46 in place for the drilling process.

At the conclusion of the drilling operation illustrated in Figure 11, the blade forging has four points of reference. Two of these points are buttons 31 and 32 which define the axis through the blade portion of the final blade and the positions of the various airfoil sections along the blade. Secondly, the ends of the root portion have been machined to an equal length relative to the button 31 and the axis extending through buttons 31 and 32. Finally, a hole has been provided in boss 33 which is along the axis formed by buttons 31 and 32. Any one or combination of these references may be used in the further machining operations.

In Figure 12, the forging is shown positioned in a lathe for grinding the leading and trailing edges of the airfoil section. As shown in the figure, the forging is supported by the headstock of the lathe engaging the ends of root portion 30 which have been previously and accurately located relative to the axis through the final blade by means of above-described operations. The mounting hole in the boss 33 provided by the above-described drilling operation is used to support the opposite end of the blade in the tail-piece of the lathe. Thus, the forging is accurately rotated about the blade axis and grinding operations may be conducted with assurance that the final surfaces will be correctly positioned and adequate material will be available on all sides.

In the final stages of blade manufacture, the root portion is milled along an axis relative to the final blade axis corresponding to the final position desired of the blade. This may be accomplished, for example, by positioning the blade in a milling machine by the hole in boss 33 and the ends of the root portion in a manner similar to that of Figure 12. The blade is thus accurately located in the milling machine and cutter op-

erations may be conducted with assurance, thus producing a final milled blade of the shape shown in Figure 13.

In Figure 14 the final broaching operation has been completed. In this case button 31 on the root portion 30 of the blade has been removed and this portion of the blade cut down to provide extension 52 which is used to bottom the blade in a groove of a compressor wheel for a jet propulsion engine (not shown).

A later step in the blade-production process is cutting the end of the blade portion 47 relative to the surface of the root portion. At this time the button 32 on the blade portion is removed and a blade such as shown in Figure 15 is provided. The ends of the root portion are then beveled to provide the final blade shown in Figures 16 and 17, Figure 17 being a top view of the final structure.

It will be apparent to those skilled in the art that, while I have shown buttons 31 and 32 positioned along the blade axis of the forging, they may be placed at any points on the blade having known relation to the airfoil sections and axes of the finished blade. Thus, for example, one button can be placed on the intersection of the root portion and blade portion and the other located on the root portion, thereby enabling the blade axis to be positioned by the known relation between the axis through the root portion and the axis through the blade portion and the airfoil sections to be located by reference to the axis through the root portion.

It will be apparent to those skilled in the art that I have provided an improved method of manufacturing turbine blades which does not require forgings with accurately located surfaces or an excessive allowance for error in locating the axis through the forgings. The buttons 31 and 32 provide a source of reference position independent of the dimensional errors that are inherent in the edges of the forgings and thereby provide a basic source of reference for further operations. If, for example, the blade forgings are produced in one location by one manufacturer and are sold in commerce to be used by other manufacturers in making a variety of blade configurations having different airfoil surfaces, angles of tilt, etc., the first manufacturer may place the buttons in the blade forgings and the second may use these buttons for reference with assurance that they will be within predetermined limits of the actual axes through the forgings. Blade production is thereby facilitated and costs correspondingly reduced.

In the foregoing specification and the accompanying claims I have used the term "in alignment with the axis of the blade portion" to mean in a plane passing through the axis of the blade portion and substantially normal to the plane of the blade blank. Similarly, by the term "in alignment with the axis of the root portion" I mean located in a plane passing through the axis of the root portion and substantially perpendicular to the plane of the blade blank.

While I have shown and described a particular arrangement of my invention, it will of course be understood that I do not wish to be limited thereto since many modifications both in the structures disclosed and the arrangement of the processes may be made without departing from the spirit and scope thereof. I, of course, contemplate by the appended claims to cover any such modifications as fall within the true spirit and scope of my invention.

I claim as my invention:

1. In a method of making turbine buckets, the improvements which comprise die-forging a metal blank having an anchoring root at one end, an extending portion at the other end, and an air foil portion between said ends, said anchoring root being in angular relation to the air foil portion and said extending portion projecting longitudinally beyond the air foil portion, simultaneously with said die-forging that produces said blank with said root, said extending portion, and said air foil portion forging on one face of the blank a first button on the root portion and a second button on the extending portion beyond the air foil portion, said buttons lying on a selected center line of the blank, engaging the buttons in recesses to hold the blank against lateral and longitudinal shifting, machining opposed surfaces of the root portion of the thus held blank whereby said surfaces will be gauged from the buttons, anchoring said opposed machined surfaces in a fixture to secure the blank, removing the first button from the root while machining the root of the thus secured blank to finished dimensions whereby the finished root surface will be gauged from said opposed surfaces and will be finished in accurate relation to the air foil portion, and cutting the extending portion and button thereon from the air foil portion to produce a turbine blade having an anchoring root and an air foil portion projecting therefrom.

2. The method of manufacturing by forging and finishing operations turbine blades and the like articles consisting of air foil portions and anchoring roots located in exact angular relation and position relative to the air foil portions, the improvements which comprise forming by die-forging a blank having an intermediate air foil portion, a root portion at one end thereof in angular relation to the air foil portion and a longitudinally extending portion at the other end thereof, simultaneously with said die forging to produce said blank having said air foil portion, said root portion, and said extending portion forging on one side of the blank first and second locating buttons in spaced relation and lying on a selected center line of the air foil portion, said first button being located on the root portion in longitudinally spaced relation to the air foil portion and said second button being located on the extending portion in longitudinally spaced relation to the air foil portion, engaging the buttons in anchoring recesses including a first recess for the first button which surrounds the button to hold it against lateral and longitudinal movement and a longitudinally elongated V-shaped slot for the second button holding the second button against lateral displacement to coact with the first recess in aligning the blank along the center line of the air foil portion, machining the thus anchored blank, gauging the machined portions of the blank from the thus anchored buttons, machining the root portion to finished dimensions, removing the first button in machining the root portion to finished dimensions, and cutting off the extending portion from the end of the air foil section thereby removing the second button without machining or grinding the air foil portion.

3. The method of making turbine blades which comprises forming a starting blank with a thickened portion at one end and an elongated shank portion extending therefrom, die-forging said blank to form a blade blank with a root portion

10
15

composed of metal from the thickened portion of the blank, an air foil portion composed of metal from the shank portion of the blank, and an undeformed end portion beyond the blade portion, simultaneously with the formation of said blade blank forming a fixed button on the root portion and a second button spaced materially from the first button on the portion of the blank beyond the blade portion and aligned with the longitudinal axis of the blade on the same side of the blank as the first button, seating the buttons in recesses coacting with the buttons to hold the blade blank against lateral and longitudinal shifting, machining the thus held blade blank, gauging the machined portions from the thus held blade blank, cutting off the end portion of the blade blank beyond the specified blade length thereby removing the second button, and machining the root to finished dimensions thereby removing the first button.

20
25
30
35
40

50

4. The method of making turbine blades which comprises forming a starting blank with a thickened portion at one end thereof and an elongated shank portion extending therefrom, die-forging said blank to form a blade blank with a root portion composed of metal from the thickened portion of the blank, an air foil portion composed of metal from the shank portion of the blank, and an undeformed end portion beyond the blade portion composed of shank metal beyond the blade portion, said root portion having its longitudinal axis at an angle to the longitudinal axis of the blade portion, simultaneously with the formation of the blade blank forging a pair of upstanding buttons at opposite longitudinal end portions of the blade blank and in materially spaced relation from each other on one face of the blank, said buttons coacting to define a longitudinal axis through the center of the blade blank and one of said buttons on said blade axis having an abutment surface adapted to hold the blade in fixed longitudinal position, seating the buttons in recesses coacting with the buttons to hold the blade blank against lateral and longitudinal shifting, trimming the thus held blade blank to remove excess metal, successively machining and broaching the trimmed blade blank to fixed dimensions gauged from said buttons, and cutting off the undeformed shank end portion of the blade blank.
